WIRE DRAWING MACHINE

Myles Morgan and Weld Morgan, Worcester,
Mass., assignors to Morgan Construction Co.,
Worcester, Mass., a corporation of Massachu-
setts

Original application March 5, 1937, Serial No.
129,232. Divided and this application June 30,
1939, Serial No. 282,236

7 Claims. (Cl. 205—14)

This invention relates to wire-drawing machines, and more particularly to machines of the type having a series of dies through which the wire is drawn by means of rotating drums or blocks to effect successive reductions of the wire. This application is a division of our prior application Serial No. 129,232, filed March 5, 1937, now Patent No. 2,185,416, issued January 2, 1940.

In the drawing of wire at high speeds, large quantities of heat are generated. The drums and wire tend to become very hot, and there is danger of the wire reaching such a high temperature as to affect its metallurgical properties in a harmful manner. This has been recognized, and various attempts have been made to cool the wire by means of air jets directed against the convolutions of wire on the drum. However, the constructions heretofore proposed have been complicated, expensive and comparatively ineffective for the purpose intended.

It is accordingly one object of the invention to provide a simple and inexpensive construction for a wire-drawing machine, whereby the drums and the wire may be effectively cooled.

It is a further object of the invention to provide a hollow wire-drawing drum arranged to direct jets of air upon the wire in a novel and highly effective manner.

It is a further object of the invention to provide an improved means for supporting and driving a wire-drawing drum, whereby the drum itself may be of relatively light and inexpensive construction, and its replacement may be facilitated.

With these and other objects in view, as will be apparent to those skilled in the art, the invention resides in the combination of parts set forth in the specification and covered by the claims appended hereto.

Referring to the drawing illustrating one embodiment of the invention and in which like reference numerals indicate like parts,

Fig. 1 is a front elevation of a wire-drawing machine; and

Fig. 2 is an enlarged section on the line 2—2 of Fig. 1.

The embodiment illustrated comprises a series of two preliminary drawing drums or blocks 10 and 11, and a finishing drum 12, all three of the drums being rotatable about vertical axes located in a common vertical plane. A suitable die 14 is mounted in advance of each drum, the drums serving to draw the wire W through the dies and thus effect successive reductions of the wire. Each die 14 is mounted on a cover plate 15 se-

cured to the top of a frame 16, this frame being arranged to form an elongated hollow box-like structure.

The drum 10 is mounted on the upper end of a vertical spindle 18 and directly above a circular opening 19 in the cover plate 15. The spindle extends downwardly through the opening 19 into the frame 16 and is rotatably supported just below the drum by an anti-friction bearing 20 carried by a bracket 22 mounted in the frame. The drum 10 is constructed with a substantially cylindrical portion 24 having spaced upper and lower flanges 25 and 26 projecting outwardly therefrom and inclined slightly with respect thereto. This construction makes possible an advantageous arrangement of the dies with respect to the drums, whereby the wire may be properly aligned with the dies without the use of idler sheaves. As shown in Fig. 1, the wire leaves the first die 14 and engages the surface 20 of the lower flange 26 of the first drum 10, thence passing around the cylindrical portion 24 of the drum in the form of a right hand helix with a sufficient number of wraps to ensure full capstan effect without slippage, and leaving the drum 25 tangentially at a point close to the upper flange 25. The second die 14 is located at a higher elevation than the first die and in direct line with the wire leaving the drum 10, the wire passing directly through this die and into engagement with the upper flange 25 of the second drum 11. The wire then passes around the cylindrical portion of the drum 11 in the form of a left hand helix and leaves the drum tangentially at a point close to the lower flange 26 thereof. This arrangement may be continued throughout the entire machine, regardless of the number of drums, the wire passing around the drums alternately in the form of right and left hand helices. The dies are located alternately in line with the lower flanges and the upper flanges, so that the wire is wound around the drums first upwardly and then downwardly. The arrangement is such that the wire is wound upwardly on the finishing drum 12, and this drum is made without an upper flange, having instead the usual stripper 28 which serves to support the coil of finished wire. With this construction it is possible to make all the drums alike (except the finishing drum), and mount all of the drums at the same elevation.

Means is preferably provided to cool the drums and the wire which is wound thereon, in order to prevent overheating of the wire as a result of the heat generated in the drawing operation. For this purpose a fan 30 is provided to discharge air

into the hollow frame 16. This fan is shown located at the finishing end of the machine. It will be apparent from Fig. 2 that the air flows from the upper portion of the frame 16 upwardly 5 through the openings 19 in the cover plate 15 and thus into the interior of the drums. In order to prevent excessive leakage of the air between the drums and the cover plate, each drum is formed with a depending skirt 32 which fits 10 closely within an annular flange 33 extending upwardly from the cover plate. The air is discharged from the interior of the drums through a series of openings 34 and 35 provided in the outwardly extending flanges 25 and 26 respectively. 15 The air is directed to the upper openings 34 by means of a circular cap 37 which engages the upper flange 25 outwardly of the openings, this cap being held in place against the upper end of the spindle 18 by means of a screw 38. As 20 shown in Fig. 2, the openings 34 and 35 are staggered in a direction circumferentially of the drum, so that the air jets do not impinge directly upon one another.

In order to facilitate the removal and replacement of the drums, each drum is provided with an inwardly extending annular flange 39 which is formed with a series of holes to receive dowel pins 40 carried on the rim of a spider 41. This spider is keyed to the upper portion of the spindle 18, and provided with apertures 43 through which the air may flow upwardly to reach the openings 34. It will be apparent that after removal of the single screw 38 the cap 37 and the drum therebeneath can be readily removed from the spider 35 41.

In the operation of the machine the drums and the wire coiled thereon are effectively cooled by the air which flows upwardly through the drums and issues in jets through the openings 34 and 40 35. The cooling action is considerably enhanced by the use of the opposed series of jets in the staggered arrangement disclosed. After a long period of use the drums will become worn, and since most of the wear will occur near the flange 45 25 or 26 which is first engaged by the wire, it is possible to interchange two adjacent drums and thereby double their useful life. The drums are of comparatively light and inexpensive construction, since they have no central hub and are supported entirely by the spiders 41. By utilizing the 50 hollow box-like frame 16 as a means for distributing the air to the several drums, we avoid the necessity for unsightly and bulky external air ducts.

55 Having thus described our invention, what we claim as new and desire to secure by Letters Patent is:

1. A wire-drawing machine comprising a hollow rotatable drum having a substantially cylindrical portion, a pair of spaced flanges extending outwardly from the cylindrical portion, and means to supply air under pressure to the interior of the drum, both of said flanges having apertures

therein arranged to direct jets of air over the surface of the cylindrical portion from opposite directions.

2. A wire-drawing machine comprising a hollow rotatable drum having a substantially cylindrical portion, a pair of spaced flanges extending outwardly from the cylindrical portion, and means to supply air under pressure to the interior of the drum, both of said flanges having apertures therein arranged to direct jets of air over the surface of the cylindrical portion from opposite directions, the apertures in the respective flanges being staggered in a direction circumferential of the drum.

3. A wire-drawing machine comprising a rotatable spindle, a spider mounted on the spindle, a drum supported on the spider and having a substantially cylindrical portion, a flange extending outwardly from the cylindrical portion and provided with a series of apertures, means to supply air under pressure to the interior of the drum, and a cap engaging the flange outwardly of the apertures, the cap serving to hold the drum in place on the spider and to direct the air into the apertures.

4. A wire-drawing machine comprising a hollow frame shaped to provide an elongated air chamber having a series of openings therein, means to supply air under pressure to the air chamber and a series of hollow rotatable drums 30 mounted adjacent said openings and arranged to receive air therefrom, said drums having apertures therein for the discharge of the air from the interior of the drums into cooling relation with wire wound about the drums.

5. A wire-drawing machine comprising a rotatable spindle, a spider fixed to the spindle, an annular drum surrounding the spindle and having an inwardly extending annular flange which engages the spider, means connecting the spider 40 to the flange to prevent relative rotation of these parts, and a cap engaging the drum to hold the drum in place on the spider.

6. A wire-drawing machine comprising a rotatable spindle, a spider fixed to the spindle, an annular drum surrounding the spindle and having an inwardly extending annular flange which engages the spider, dowel pins connecting the spider to the flange to prevent relative rotation of these parts, and a cap releasably fastened to the 50 end of the spindle to hold the drum in place on the spider.

7. A wire-drawing machine comprising a hollow rotatable drum having a substantially cylindrical portion, a flange extending outwardly from the cylindrical portion and provided with a series of apertures, means to supply air under pressure to the interior of the drum, and a cap rotatable with the drum and engaging the flange outwardly of the apertures, the cap serving to direct the air into the apertures.
